UNITED STATES PATENT OFFICE.

SAMUEL MAWHINNEY, OF WORCESTER, MASSACHUSETTS, ASSIGNOR TO TYLER HINGED LAST COMPANY, OF CHARLESTON, WEST VIRGINIA, AND BROCKTON, MASSACHUSETTS, A CORPORATION OF WEST VIRGINIA.

LAST AND HINGE.

SPECIFICATION forming part of Letters Patent No. 721,717, dated March 3, 1903.

Application filed March 25, 1902. Serial No. 99,843. (No model.)

To all whom it may concern:

Be it known that I, SAMUEL MAWHINNEY, a citizen of the United States, residing at Worcester, in the county of Worcester and 5 State of Massachusetts, have invented certain new and useful Improvements in Lasts and Hinges, of which the following is a specification, reference being had therein to the accompanying drawings.

10 My invention is an improvement on the last described and shown in United States Letters Patent No. 601,622, granted to Abel D. Tyler, Jr., March 29, 1898.

In the drawings illustrating the principle 15 of my invention and the best mode now known to me of applying that principle, Figure 1 is a side elevation of a part of a last, a portion of the fore part being broken away to show the hinge member therein. Fig. 2 is a top plan 20 view of what is shown in Fig. 1. Fig. 3 is a central vertical sectional view on line A A of Fig. 2. Fig. 4 is a plan view of the fore-part hinge member. Fig. 5 is a perspective view 25 of what is shown in Fig. 4. Fig. 6 is a detail view showing in perspective the hinge mechanism which connects the heel part and the fore part. Fig. 7 is a detail showing the cap and its coacting spring.

The fore part 1 and heel part 2 are joined 30 by a hinge connection, the open space 3 permitting these parts to be tipped up relatively to each other, as is indicated by the dotted lines in Fig. 3. The inner end wall 4 of the heel part and the inner end wall 5 of the fore 35 part form what may be termed "reciprocal hinged surfaces," these two walls abutting when the parts are tipped up relative to each other, as shown by the dotted lines in Fig. 3.

Cast integral with the heel-plate 6 is the 40 spindle-socket 7 and the heel-part hinge member 8. (See Fig. 6.)

The spindle-socket 7 is adapted to receive a spindle in the ordinary use of the last, and inserted therein is a plug 23, which rests on an 45 inwardly-projecting annular rim 29 and resists the end thrust of the spindle when the heel part is forced thereon.

A wooden plug 28 is inserted in the lower end of the spindle-socket 7 to receive a last- 50 ing-tack.

The heel-part hinge member 8 extends upwardly and forwardly from the heel-plate 6, as is clearly shown in Fig. 6, and the upper front portion 9 of the said hinge member 8 is provided with a pintle-bearing 10, adapted to 55 receive the hinge-pintle 11.

The fore-part hinge member 12 (see Figs. 4 and 5) is preferably formed by bending sheet metal on itself, each fold having a lobe 14, concave on its inner side. The two concave lobes register with each other, so as to form a chamber 15, extending lengthwise of the last. This hinge member 12 is secured in the fore part by fasteners 16, (see Figs. 1, 2, and 3,) which pass through the fore part and 60 holes in the hinge member 12. Formed on the hinge member 12 are ears 17 and 18, adapted to receive the pintle 11.

The pintle-bearing 10 of the heel-part hinge member 8 enters the space 19^x between the 70 ears 17 18 of the fore-part hinge member 12, and these two coacting hinge members are secured together by the pintle 11, as is clearly shown in Fig. 6. The pintle-ears 17 18 are preferably of unequal widths, as shown, so that the 75 fore-part hinge member 12 may be used one side up in right lasts and the other side up in left lasts.

The top surface 19 of the end portion 9 of the heel-part hinge member 8 is a cam-surface, and the said end portion 9 is also formed with a shoulder or bearing 20, against which the cap 21 (see Figs. 7 and 3) is forced by the spring 22. The said cap 21 is slidably mounted in the chamber 15, and when the heel part 80 is tipped up relatively to the fore part, or vice versa, the cam-surface 19 engages the outer end of the cap 21, the cap being thereby moved toward the toe against the tension of the spring. The fore part and heel part 90 are kept in alinement in the position shown in Fig. 1 by the spring 22 pressing forcibly the cap 21 against the shoulder 20. Through the hole 30 in the spindle-socket 7 and through the wooden plug 28 passes a fastener 95 24, which secures the said spindle-socket 7 in place in the heel part 2. (See Figs. 6, 2, and 3.)

The heel-part hinge member 8 is mounted in the vertical slot 26 in the heel part 2 and 100

is held securely therein by a fastener 25, which passes through the heel part and a hole 27 in said hinge member 8.

It is not necessary to my invention that the 5 spindle-socket 7 be integral with the heel-plate 6 or the hinge member 8, for all three parts may be separated, if preferred.

What I claim is—

- 10 1. The combination, in a transversely-di- vided last, of a fore part and heel part with a hinge, one member of which is secured to the heel part, and the other member of which is secured to the fore part, one of said mem- bers having a pintle-bearing, and the other 15 member having two pintle-receiving ears, one of which is narrower than the other.
- 15 2. In a transversely-divided hinged last,

the combination of a heel part and fore part with a hinge, the heel-part member of which comprises an integral heel-plate, spindle-socket and forwardly-extending cam and lateral pintle bearing; and the fore-part mem- ber of which comprises a plate bent on itself having two pintle-receiving ears, one of which is wider than the other, and intermediate 25 said ears, a spring-receiving chamber extend- ing lengthwise of the last; and a spring in said chamber.

In testimony whereof I affix my signature in presence of two witnesses.

SAMUEL MAWHINNEY.
